[57] **ABSTRACT**

[21] Appl. No.: **448,310**

A gas turbine compressor comprising a rotor disc has continuous flow bleed vanes attached thereto. The bleed vanes are channel shaped members attached to the downstream side of the rotor disc near its periphery and between adjacent blades. The bleed vanes direct the compressible fluid radially inwardly between the rotor disc and a coolant guide disc attached to the downstream side of the rotor disc. The bleed vanes minimize the difference in tangential velocities of the extraction flow and the rotor disc speed at the inlet region of the continuous bleed system. The extracted fluid is ducted thereafter to a turbine where it is employed for cooling purposes.

FIG.1

FIG.2

FIG.3

FIG.4

FIG.5

TURBOMACHINE EXTRACTION FLOW GUIDE VANES

BACKGROUND OF THE INVENTION

1. Field of the Invention

This invention relates to compressors for gas turbines, and more particularly to such structures adapted for continuously bleeding air from the compressor.

2. Prior Art

Gas turbine engines often include a compressor structure which permits extraction or bleeding of the compressible fluid, usually air, from between two of the downstream stages of the compressor, or from the last stage of the compressor, to provide pressurized air for cooling purposes or for accessory use.

The turbomachine extraction or bleed systems for the compressors require minimization of pressure losses within the system. Present designs employ valves and ports in annular arrays disposed radially outwardly of the blades. These arrays are often complicated mechanical systems. They are heavy and they increase the dimensions of the equipment. Plenum structures must be accommodated for these bleed systems. Special ducting, bridging and external piping must also be employed with many of the prior art extraction systems.

To this end, in accordance with the objects of the invention, the applicant has invented a novel structure in which a final or intermediate stage continuous bleeding of a compressor is maintained internally, while minimizing the complexity of the machine, minimizing the total pressure losses, and overcoming the objections to the prior art.

SUMMARY OF THE INVENTION

The present invention provides a simple, yet effective structure for extracting fluid from the flow path of a compressor. This is accomplished by providing channel shaped members disposed on the downstream side of the rotor disc. The channel shaped members have leg portions directed upstream and the leg portions are formed about the steeples on the rotor disc. The channel shaped members duct the compressed fluid radially inwardly between the rotor disc and a coolant guide disc. The fluid is then channeled to portions of the turbine for cooling purposes. The pressure losses of the fluid are reduced to a minimum and the tangential velocity of the compressed fluid with respect to the rotor disc is reduced to zero as the fluid enters the bleed system.

BRIEF DESCRIPTION OF THE DRAWINGS

The invention, along with the objects and advantages thereof will be best understood from the following detailed description taken in conjunction with the accompanying drawings in which:

FIG. 1 is a perspective view of a portion of the downstream side of a compressor rotor disc showing an extraction vane mounted thereon;

FIG. 2 is a perspective view of a portion of the upstream side of a compressor rotor disc showing the extraction vane mounted therewith;

FIG. 3 is a view directed radially inwardly on a compressor disc showing a few of the blades, and the extraction vanes mounted therewith;

FIG. 4 is an alternative embodiment of the extraction vane shown in FIG. 1;

FIG. 5 is a perspective view of a portion of a com-

pressor rotor disc and a guide disc downstream thereof;

FIG. 6 is a side sectional view of a last stage compressor rotor disc having extraction vanes and a guide disc mounted thereon; and,

FIG. 7 is a side sectional view of an intermediate stage compressor rotor disc having extraction vanes and a guide disc mounted thereon.

DESCRIPTION OF THE PREFERRED EMBODIMENT

Referring to the drawings in detail, and particularly to FIG. 1, there is shown a compressor rotor disc 10. Compressors are usually comprised of a series of these rotor discs mounted axially together and disposed in a

15 housing. The discs have airfoil shaped blades, not shown, mounted thereon to cause compression upon the fluid flowing therewith. The rotor disc 10 shown in FIG. 1 for this example, is a last stage disc. The rotor disc 10 has a plurality of grooves 12 disposed on its periphery. The grooves 12 receive root portions of airfoil blades, not shown. A steeple 14 is disposed between adjacent grooves 12. The fluid, which may be air or helium, flows over the steeple 14, the flow path being indicated by the arrow A, as it is compressed in its course 20 through the compressor. A small portion of this fluid is drawn into an air bleed vane 16 disposed about the downstream side of the steeple 14. The air bleed vane 16 is a generally channel shaped member having leg portions 18 and 18', formed around the walls of the grooves 12 and directed upstream. The bleed vane 16 is also comprised of a radially directed generally U-shaped member 20. The U-shaped member 20 has a wall portion 22 whose radially innermost portion gradually curves away from the steeple 14, as shown in FIG. 25

1. This permits the securing of the bleed vane disc by the utilization of an annularly shaped guide disc 24 in addition to the securing of a bleed vane 16 by the use of leg portions 18 and 18'. The guide disc 24 is shown further in FIGS. 5, 6 and 7.

40 The bleed vane 16 has tabs 26 and 26' that are bent around the upstream side of the steeple 14, as shown in FIG. 2. The tabs 26 and 26', are the end portions of the leg portions 18 and 18', respectively. When the blades, not shown in this figure, are inserted into their grooves 12, they frictionally engage the leg portions 18 and 18' of the bleed vane 16 and also by a wedging action, help secure the bleed vanes to the rotor disc 10.

The guide disc 24 is disposed downstream of and adjacent to the bleed vanes 16 as indicated by the dotted lines in FIG. 3. A plurality of airfoil blades 28 are shown disposed in the grooves 12 on the disc 10. The sides of the blade roots are shown wedging the leg portions 18 and 18', close to the steeples 14. The fluid, as shown by vector V1, in FIG. 3, enters the bleed vane 16 and is turned to the axial direction, indicated by vector V2, simultaneously as it is directed radially inwardly. The tangential velocity, indicated by the vector Vθ, is reduced to zero relative to the rotor disc 10, as the fluid flow enters the bleed system.

55 50 A slight modification of a portion of the bleed vane 16, is shown in FIG. 4. The U-shaped channel member 20 has one side 21 that is radially shorter, as indicated by the letter B in FIG. 4, than are the other walls of the channel member 20. The wall 21 of the channel 20 in the direction of disc rotation being radially shorter than the other walls permits an added inducement of fluid flow through the channel member 20. Also, in either

60 65

case the area between the bleed vane 16 and the guide disc 24 will be of lower pressure than the pressure in the motive fluid flow path so as to draw the fluid therethrough.

A portion of the annularly shaped guide disc 24 for a last stage rotor is shown in FIGS. 5 and 6. The guide disc 24 is bolted to the rotor disc 10 by an annular array of bolts 30. A radial array of ducts 32 permits the fluid to flow between the rotor disc 10 and the guide disc 24 from where it will be channeled to critical areas requiring cooling fluid or pressurized fluid.

Also shown in FIG. 6, is a portion of a compressor housing 34 having annular arrays of stationary blades 36. An additional rotor disc 37 is shown upstream of the disc 10. The curved wall portion 22 of U-shaped channel portion 20 is shown in a close fitting restrained relationship with the guide disc 24.

As is well known in the art, the fluid is drawn through the compressible fluid flow path, indicated by the letter C. The area of the flow path is reduced as the fluid is drawn therethrough. The compressed fluid is ducted to a combustion area of a turbine, not shown, for mixture with fuel to drive the turbine.

A portion of the compressed fluid as indicated in this invention is continuously drawn through bleed vane 16 due to the pressure difference between the fluid flow path C and the fluid extraction route as indicated by the letter D in FIG. 6.

An alternative arrangement is shown in FIG. 7, wherein a portion of a compressor 40 has an annular array of bleed vanes 16 and a guide disc 42 disposed on an intermediate rotor disc 44, and wherein a last stage rotor disc 46 does not have a bleed system disposed thereon. An array of stationary airfoil shaped blades 48 is disposed between annular arrays of rotating airfoil shaped blades 50 and 52 respectively. The fluid is continuously extracted through the bleed vane 16 as was shown in the prior figures. The fluid in this embodiment however, follows the path indicated by the arrows "E," around connecting bolts 53 into a coolant passageway 51.

From the foregoing description it should now be apparent that a new and useful continuous bleed vane structure has been disclosed for axial flow compressors, in which channel shaped members are disposed on the downstream side of steeple between adjacent rotor blades, and an annularly shaped guide disc is disposed on the downstream side of the rotor disc, between which are disposed an annular array of channel shaped members to help duct the fluid to an area in the turbine for cooling purposes. The guide disc also helps secure the channel shaped member to the rotor disc.

Though the invention has been described with a certain degree of particularity, changes may be made

therein without departing from the scope thereof. For example, the invention has been applied to only one of a plurality of rotor discs. Obviously a plurality of such discs could be used simultaneously, or the channel members could be modified to increase the flow rate therethrough.

I claim as my invention:

1. An axial flow compressor having a continuous fluid bleed system including:
  - 10 at least one rotor disc in said compressor; a plurality of generally axially directed grooves on the periphery of said rotor disc; an annular array of radially directed airfoil blades supportively disposed in said grooves;
  - 15 extraction flow guide vane means attached to the side of said rotor disc, said extraction flow guide vane means comprising generally channel shaped members directed radially inwardly, said channel shaped members being attached to the downstream side of said rotor disc, adjacent the periphery of said disc, and disposed between adjacent turbine blades, said generally channel shaped members having generally parallel leg portions, one leg of each channel shaped member being restrained from dislocation by being attached to a wall of one groove on said disc, the other leg of each of said channel shaped members being attached to an adjacent wall of an adjacent groove on said disc, said legs of said channel shaped members being additionally restrained from dislocation by the wedging action of said blades holding said legs between themselves and said walls of said grooves;
  - 20 a coolant flow guide disc attached to the downstream side of said rotor, said coolant flow guide disc guiding the extracted fluid generally radially inwardly adjacent said rotor disc.
2. An axial flow compressor arrangement as recited in claim 1, wherein one generally channel shaped member is disposed between adjacent blades.
3. An axial flow compressor as recited in claim 1, wherein said leg portions of said channel shaped members are attached to said rotor disc by bending the leg portions to conform to the groove wall and rotor disc configurations.
4. An axial flow compressor as recited in claim 3, wherein said leg portions of said generally channel shaped members are directed in the generally upstream direction.
5. An axial flow compressor as recited in claim 4, wherein said generally channel shaped members have downstream wall portions, said downstream wall portions being generally curved to mate with said guide disc in a restraining relationship.
